INTERLOCKING SKIP LOADING SYSTEM

Application filed June 27, 1928, Serial No. 288,658. Renewed December 29, 1931.

The present invention relates to interlocking skip loading systems.

More particularly the present invention relates to a system for operating and controlling a pair of connected skip tubs or the like, such as are used in the loading of blast furnaces. It will be understood as the description proceeds, however, that the invention is not limited to the loading of blast furnaces 10 or the operation of loading skips, but has a much broader application. For purposes of this description, however, the invention will be described with reference to blast furnace practice.

15 An object of the present invention is to provide a system involving the use of a pair of skip tubs which are connected together, whereby, when one of said tubs is at the bottom of its travel, the other of said tubs will be at the top of its travel; which system is provided with protective means for insuring that dumping of material intended for one or the other of said tubs will occur only when said tubs are in predetermined positions.

25 Another object of the invention is to provide a blast furnace loading system involving a pair of cooperating skip tubs; which system is provided with protective means which will prevent the scale car operator from dumping 30 either of the usual compartments, or hoppers, of a scale car unless said compartment, or hopper, is spotted directly over a skip tub, thereby making it impossible for him to dump the material into the skip pit; as for 35 example, when said skip tub is not in proper position.

A further object of the invention is to provide a system involving a pair of interconnected skip tubs and a scale car for dumping 40 selectively into said skip tubs; which system is simple in operation; relatively cheap to construct; and which is provided with protective means for insuring that the scale car operator will not dump from the scale car except when the skip tub is in proper position to receive the material dumped from said scale car.

45 A still further object of the invention is to provide a loading system involving a pair of skip tubs; which system is well adapted

to meet the needs of commercial operation.

These and other objects of the invention will become more readily apparent in the course of the following description of the preferred embodiment of the invention, taken in connection with the accompanying drawings, 55 wherein

Fig. 1 is a more or less diagrammatic view, showing in section part of the loading system of a blast furnace;

Fig. 2 is a cross-section, taken on the line 2—2 of Fig. 1, and

Fig. 3 is a diagrammatic view, illustrating certain electrical features of the structure shown in Figs. 1 and 2.

60 The numeral 1 indicates a pit, the ground or floor level being indicated by the numeral 2. Extending into said pit is an inclined track structure including runways 3 and 4 for the skip tubs 5 and 6. The skip tubs 5 and 6 are connected together by means of a cable 7 which runs over a sheave (not shown), located at a region above the upper limit of travel of the two skip tubs 5 and 6. In Figs. 1, 2, and 3 the skip tub 6 is shown at 65 the lower limit of its travel in position to be loaded. In Fig. 1, the skip tub 5 is shown at the upper limit of its travel in position to dump its contents into a blast furnace or the like. The means for operating the cable 7 is 70 not shown, but it will be understood that power may be communicated to the cable by means of a drum driven by a hoisting engine or the like.

75 Disposed in position to discharge material 85 into the two skip tubs 5 and 6, are the chutes 8 and 9. Said chutes communicate at their upper extremities with the hopper 10, which may contain a supply of coke. The hopper 10 is provided with a pair of gates 11 and 12 90 (one for each chute), respectively adapted to be opened and closed by means of coke gate motors 13 and 14.

95 Also disposed in position to discharge material into the two chutes 8 and 9, are the hoppers 15 and 16, adapted to receive material from the scale car 17. As indicated in dotted lines in Fig. 3, a scale car 17 of usual construction includes a pair of hoppers 18 and 19. When the gate at the bottom of 100

either of the hoppers 18 or 19 is opened, material from said scale car (assuming that the scale car has been properly spotted) will discharge into one or the other of the hoppers 15 or 16, to be delivered into one or the other of the skip tubs 5 or 6.

The present invention contemplates interlocking mechanism whereby the operator may not discharge from either hopper 18 or 19, unless that particular hopper is properly spotted over a skip tub. As the scale cars are ordinarily manufactured, the operator controls the opening of the gate for the discharge of material from said scale car. According to the present invention, even though the scale car operator should attempt to operate the gate communicating with either hopper 18 or 19, he will not be able to accomplish this result, unless, by reason of the proper positioning of the scale car and skip tubs, one of said skip tubs is in position to receive the discharged material.

In order to illustrate this feature of the present invention, a preferred embodiment involves a pair of power conductors 20a and 20b, which may be connected to the two sides of an electrical circuit 21a and 21b through a cutoff switch 22. Mounted on the frame of the skip hoist drum (not shown) is a pair of normally open limit switches 23 and 24, one terminal of each of which is connected to the power conductor 20a by means of a suitable conductor 25. These limit switches are adapted to be closed by an operating nut 26, which travels on a screw 27, which in turn may be actuated, or rotated, by the rotation of the skip hoist drum.

The scale car 17 is provided with two pairs of sliding contact shoes 28a, 28b, and 29a, 29b. The contact shoes 28a and 28b are connected to the terminals of a solenoid 30, and the contact shoes 29a and 29b are connected to the terminals of a solenoid 31. The solenoids 30 and 31 are respectively adapted to permit the operation of air cylinders 32 and 33, which respectively function to open and close the gates of the scale car hoppers 18 and 19, as shown in Fig. 2. Air will be admitted to the air cylinders 32 and 33 only when their respective solenoids 30 and 31 are energized.

When skip tub 6 is in its lowermost position, as shown in Figs. 1, 2, and 3, limit switch 24 is closed, forming a closed circuit as follows: power conductor 20a, conductor 25, limit switch 24, conductor 34, solenoid cutoff switch 35, conductor 36, conductor bar 37 (mounted on coke hopper 10, directly over the center of coke chute 9), scale car conductor shoe 28a, conductor 38, solenoid 31, conductor 39, scale car conductor shoe 29b, conductor bar 40 (mounted on coke hopper 10, below conductor bar 37), conductor 41, switch 35, and power conductor 20b. With the circuit thus closed, the solenoid 31 is en-

ergized, and the scale car operator may open the gate of the hopper 19, and thereby discharge the contents of the hopper into the skip tub 6.

If it is desired to discharge coke from the hopper 10 into the skip tub 6, this may be done by the operator through the intermediary of the coke gate motor 14 (shown in Fig. 2), the terminals 42 and 43 of which, are connected to the power conductors 20a and 20b through suitable circuit breakers (not shown). These circuit breakers may be energized to cause the motor 14 to open and close the coke gate 12, at will, by means of a manually controlled switch 44.

On moving the switch 44 to the position indicated in dotted lines in Fig. 3, a closed circuit is formed, including power conductor 20a, conductor 25, limit switch 24, conductor 34, conductor 45, cutoff switch 46, conductor 47, switch 44, conductor 48, limit switch 49, circuit breakers (not shown) for closing the circuit in power lines 42 and 43, conductor 50, cutoff switch 46, conductor 51, and power line 20b. The closing of the aforesaid circuit in the manner described, causes the closing of the circuit to the coke gate motor 14.

After a predetermined interval, during which the gate 12 is opening, the limit switch 49 opens, and a limit switch 52 closes. The gate 12 may then be closed by moving the switch 44 to the position indicated by the dot and dash line in Fig. 3.

It will be readily understood that when the limit switch 23 is open (as shown in Fig. 3), and with the scale car 17 in the position indicated in this figure, neither the gate of the hopper 18, nor the gate 11 of the hopper 10 may be opened, and the possibility of accidental dumping of material into the pit 1 is thus completely obviated.

An indicating light 53, energized only when the limit switch 24 is closed, serves as an added precaution to indicate to the operator that the skip tub 6 is properly spotted for receiving material.

When the positions of the skip tubs 5 and 6 are reversed, that is to say, when the skip tub 5 is in its lowermost position, limit switch 23 is closed, forming a closed circuit as follows: power conductor 20a, conductor 25, limit switch 23, conductor 54, solenoid cutoff switch 35, conductor 55, conductor bar 56 (mounted on coke hopper 10, directly over the center of coke chute 8), scale car conductor shoe 28a, conductor 57, solenoid 30, conductor 58, scale car conductor shoe 28b, conductor bar 59 (mounted on coke hopper 10 below conductor bar 56), conductor 41, switch 35, and power conductor 20b. With the circuit thus closed, the solenoid 30 is energized and air is permitted to enter the cylinder 32 to open the gate of the hopper 18, and thereby discharge the contents of the hopper into the skip tub 5.

If it is desired to discharge coke from the hopper 10 into the skip tub 5, this may be done by the operator through the intermediary of the coke gate motor 13 (shown in Figs. 1 and 2), the terminals 60 and 61 of which are connected to the power conductors 20a and 20b through suitable circuit breakers (not shown). These circuit breakers may be energized to cause the motor 13 to open and close the coke gate 11, at will, by means of a manually controlled switch 62.

On moving the switch 62 to the position indicated in dotted lines in Fig. 3, a closed circuit is formed, including power conductor 20a, conductor 25, limit switch 23, conductor 54, conductor 63, cutoff switch 46, conductor 64, switch 62, conductor 65, limit switch 66, circuit breakers (not shown) for closing the circuit in power lines 60 and 61, conductor 67, cutoff switch 46, conductor 51, and power line 20b. The closing of the aforesaid circuit in the manner described, causes the closing of the circuit to the coke gate motor 13.

After a predetermined interval, during which the coke gate 11 is opening, the limit switch 66 opens, and a limit switch 68 closes. The gate 11 may then be closed by moving the switch 62 to the position indicated by the dot and dash line in Fig. 3.

It will be readily understood that when the limit switch 24 is open, and with the scale car 17 in the position indicated in Fig. 3, neither the gate of the hopper 19, nor the gate 12 of the hopper 10 may be opened, and the possibility of accidental dumping of material into the pit 1 is thus completely obviated.

An indicating light 69, energized only when the limit switch 23 is closed, serves as an added precaution to indicate to the operator that the skip tub 5 is properly spotted for receiving material.

It will be readily understood from Fig. 3 that either hopper, 18 or 19, of the scale car, may be spotted over the skip tub 6, and that said skip tub will receive material from the hopper so spotted. It will also be clear that the present invention controls the dumping from both the scale car 17 and the hopper 10.

Though a preferred embodiment of the present invention has been described in detail, many modifications will occur to those skilled in the art. It is intended to cover all such modifications which fall within the scope of the appended claims.

What I claim is:

1. In combination, a pair of skip tubs, an operating cable for moving said tubs simultaneously, a pair of hoppers for discharging into said tubs, limit switches responsive to the position of said operating cable, a pair of gates for said hoppers operable only by selective electric circuits, said electric circuits being responsive only to the cooperation of said limit switches and the position of said hoppers relative to said skip tubs.

2. In combination, a pair of skip tubs, an operating cable for moving said tubs simultaneously, a pair of limit switches responsive to the relative positions of said skip tubs, a scale car having a pair of hoppers adapted to cooperate with said skip tubs, and electric contact means carried by said scale car and adapted to complete an electric circuit through one or the other of said limit switches for selectively controlling the discharging of said hoppers, said contact means being operative only when the scale car is in position to discharge into one or the other of said skip tubs.

3. In combination, a pair of skip tubs, an operating cable for moving said skip tubs simultaneously, a scale car having a plurality of hoppers for discharging selectively into said skip tubs, means for controlling the discharge of said hoppers, a solenoid associated with each of said hoppers for controlling said means, and means adapted to complete an electrical circuit selectively through said solenoids, said last-named means having two branches and a limit switch in each of said branches, each of said limit switches being responsive to the positions of said skip tubs.

4. In combination, a skip tub, a scale car having a plurality of hoppers adapted to be selectively positioned over said skip tub to discharge material thereinto, means for discharging material from said hoppers, and means co-operating with said skip tub rendering all of said discharging means inoperative except that of the hopper which is positioned over said skip tub.

5. In combination, a skip tub, a scale car having a plurality of hoppers adapted to be selectively positioned over said skip tub to discharge material thereinto, means for discharging material from said hoppers, and electric contact devices rendering all of said discharging means inoperative except that of the hopper which is positioned over said tub.

6. In combination, a skip tub, a scale car having a plurality of hoppers provided with gates and adapted to be selectively positioned over said skip tub to discharge material thereinto, means for opening said gates to discharge material from said hoppers, and means co-operating with said skip tub for rendering all of said gate opening means inoperative except that of the hopper which is positioned over said tub.

7. In combination, a skip tub, a scale car having a plurality of hoppers provided with gates and adapted to be selectively positioned over said skip tub to discharge material thereinto, means for opening said gates to discharge material from said hoppers, and electric contact means rendering all of said gate opening means inoperative except that of the hopper which is positioned over said skip tub.

8. In combination, a pair of interconnected skip tubs adapted to be alternately positioned to receive material, a scale car having a plurality of hoppers adapted to be selectively positioned over one of said skip tubs to discharge material thereinto, means for discharging material from said hoppers, and means cooperating with said skip tub rendering all of said discharging means inoperative except that of the hopper which is positioned over one of said skip tubs.

9. In combination, a pair of interconnected skip tubs adapted to be alternately positioned to receive material, a scale car having a plurality of hoppers adapted to be selectively positioned over one of said skip tubs to discharge material thereinto, means for discharging material from said hoppers, and electric contact devices rendering all of said discharging means inoperative except that of the hopper which is positioned over said tub.

10. In combination, a pair of interconnected skip tubs adapted to be alternately positioned to receive material, a scale car having a plurality of hoppers provided with gates and adapted to be selectively positioned over one of said skip tubs to discharge material thereinto, means for opening said gates to discharge material from said hoppers, and means cooperating with said skip tub rendering all of said gate opening means inoperative except that of the hopper which is positioned over one of said tubs.

11. In combination, a pair of interconnected skip tubs adapted to be alternately positioned to receive material, a scale car having a plurality of hoppers provided with gates and adapted to be selectively positioned over one of said skip tubs to discharge material thereinto, means for opening said gates to discharge material from said hoppers, and electric contact devices rendering all of said gate opening means inoperative except that of the hopper which is positioned over one of said skip tubs.

12. In combination, material containing containers having discharge openings, gates for the openings to control discharge of material through the latter, electrical means for controlling operation of said gates, skip tubs mounted for simultaneous alternative movement into and out of material receiving position relative to the said discharge openings, respectively, means for moving the skip tubs to position to receive material from the said openings and to positions to dump material so received, limit switches shiftable with the shifting of positions of the skip tubs and an electrical circuit including said limit switches and gate controlling means for transmitting current to and energizing said gate operating means.

13. In combination, movable material containing containers having discharge open-

ings, gates for said openings, electrical means for controlling the operation of said gates, skip tubs mounted for simultaneous alternative movement into and out of material receiving position relative to said discharge openings, respectively, limit switches responsive to the position of said skip tubs, and an electrical circuit including said limit switches responsive to the discharging position of said material containing containers for transmitting current to and energizing said gate operating means.

14. In combination, material containing containers having discharge openings, means for discharging material through said openings, skip tubs mounted for simultaneous alternative movement into and out of material receiving position relative to said discharge openings, means for moving said skip tubs into and out of material receiving position, electrical means responsive to the position of said skip tubs for effecting the operation of said discharge openings.

15. In combination, material containing means having discharge openings, means for discharging material through said openings, skip tubs mounted for simultaneous alternative movement into and out of material receiving position relative to said discharge openings, and electrical means rendering all of said discharge means inoperative except that of the opening disposed over the skip tub in position to receive material.

16. In combination, two material transfer elements each movable angularly to the other, a power operable gate means between said elements, means for operating said gate means, and contact members controlled by the position of both of said elements to effect the transmission of power for permitting the operation of said gate means.

17. In combination, a skip tub, a scale car, a power operable gate means between said skip tub and said scale car, means for operating said gate means, and electrical means controlled by the action of said skip tub and scale car to turn on the power for permitting the operation of said gate means.

In testimony whereof I affix my signature.
JAMES D. KELVIE. 116
